UNITED STATES PATENT OFFICE.

FRANK A. SHERMAN AND JOSEPH M. HALL, OF HAMILTON, ONTARIO, CANADA.

METHOD AND APPARATUS FOR MAKING SHELL-FORGINGS.

1,347,415.

Specification of Letters Patent.

Patented July 20, 1920.

Application filed August 2, 1918. Serial No. 247,957.

To all whom it may concern:

Be it known that we, FRANK A. SHERMAN and JOSEPH M. HALL, citizens of the United States, and residents of Hamilton, in the 5 county of Wentworth, Province of Ontario, and Dominion of Canada, have invented new and useful Improvements in Methods and Apparatus for Making Shell-Forgings, of which the following is a specification.

10 This invention relates to a method and apparatus for making metal shell forgings such as are employed in projectiles, although the same may also be employed to advantage in producing other hollow, tubular or cup-shaped forgings for other purposes.

In the manufacture of such forgings, as heretofore practised, the die which receives the billet or blank was usually held stationary so that when this blank was subjected to 20 the endwise pressure of the mandrel or piercing pin, the metal of the blank would flow lengthwise of the bore of the die which not only required a great deal more power to produce the hollow forging but also would 25 wear the bore of the die unduly rapid so that frequent relining of the same was necessary and therefore increased the cost of production.

One of the objects of this invention is the 30 provision of a method and apparatus for making shell forgings or similar tubular or cup-shaped articles in which the blank while subjected to endwise pressure for forming the cavity therein is restrained against lateral movement but is free to move lengthwise without appreciable friction of its outer side 35 against the bore of the die, and thereby facilitate the formation of the forging as well as eliminating the excessive wear on the die.

Other objects of this invention are to provide simple means for keeping the die cool, to provide efficient means for guiding the mandrel, punch or piercing pin during its 45 working stroke and also stripping the finishing forging therefrom after the latter is completed, to provide means for ejecting the finished blank, and to improve the apparatus in other respects for increasing the 50 efficiency of the same, simplifying its construction and reducing its cost of manufacture.

In the accompanying drawings: Figure 1 is a vertical longitudinal section of a 55 practical embodiment of an apparatus for practising our invention taken on line 1—1,

Fig. 5, and showing the position of the parts when beginning a forging operation. Fig. 2 is a fragmentary vertical longitudinal section on the same line, showing the position of the parts when a forging is completed. Fig. 3 is a fragmentary vertical section taken on line 3—3, Fig. 5. Fig. 4 is a top plan view of the apparatus. Fig. 5 is a horizontal section taken on line 5—5, 60 Fig. 1. Fig. 6 is a fragmentary vertical section showing a modified form of the means for ejecting the finished forging. Fig. 7 is a sectional perspective view of the outer tubular body of the die pot showing the 70 manner of constructing the water cooling passage therein.

Similar characters of reference indicate corresponding parts throughout the several views.

In its general organization, the apparatus for practising our invention comprises a die having the form of a pot which is adapted to receive the blank or billet 1 which is to be forged into tubular or cup-shaped 80 form, and a mandrel, punch, plunger or piercing pin which engages the blank endwise. The die pot has a tubular wall and a bottom arranged within one end of the same while the opposite end of this wall is open 85 to form a mouth through which the blank is inserted into and removed from the die as the mandrel enters and leaves the same. In the preferred construction of the wall of the die pot, the same comprises an outer 90 tubular section or body 2 and a tubular lining or inner section 3 arranged within this outer section and capable of being removed therefrom so that when this lining becomes worn the same can be renewed. The bot- 95 tom of the die pot preferably comprises an outer or lower body-section 4 and an upper or inner wearing section 5 which is seated on the inner end of the bottom body section and is capable of being reversed so that its 100 opposite sides can be used successively until worn out and then replaced by another inner section.

The bottom of the die pot has its lower or outer section preferably mounted rigidly on 105 a base which is secured to the lower stationary platen of a hydraulic or similar press, this base in its preferred form comprising a central body portion 6 which is provided at its lower end with a laterally-projecting flange 7 whereby the same is connected with the lower platen of the press while its 110

upper end is provided with an annular recess 8 in which an attaching flange 9 at the lower end of the bottom body is seated and secured therein by means of bolts 10, as shown in Fig. 3, or by other suitable means. Adjacent to the recess in the body of the base, the same is provided on its upper side with an annular upwardly-facing shoulder 11 which is engaged by the lower end of the tubular body or outer section of the die pot wall and limits the downward movement of the latter. Outside of this shoulder the base is provided with an upwardly-projecting tubular guide or sleeve 12 which engages with the lower part of the periphery of the wall-body and serves together with the lower section of the bottom as a guide for the die pot in a direction lengthwise of its axis.

In order to prevent any scale or dirt which may work downwardly between the bore of the die pot lining and the periphery of the die bottom from interfering with the downward movement of the die pot in its lowermost position, the lower end of the die pot wall is provided with an annular recess 13 into which any such material is directed and gathered, thereby avoiding the objectionable effects just mentioned. For the same purpose an annular pocket or recess 14 is formed in the bore of the guide tube or sleeve 12 between its upper and lower edges, so that any dirt which may work downwardly through the joint between this guide sleeve 15 and the guide pot wall will be collected in this pocket and prevented from reaching the space between the shoulder of the base and the lower end of the die pot body which otherwise would prevent the latter from moving downwardly into its lowermost position and seat itself properly on the base. The entrance of any foreign matter, such as dirt and dust, between the die pot wall and the guide sleeve is however prevented or at least minimized as much as possible by the employment of a packing 15 which is arranged in an annular undercut rabbet or groove 16 in the upper edge of the guide sleeve and engaging with the periphery of the body of the die pot wall, and also by providing this body immediately above this packing with a laterally-projecting guard flange 17 which overhangs the upper end of the guide sleeve and the packing therein 55 and is provided with an upper outwardly-inclined surface 18 so as to shed any foreign matter laterally beyond the periphery of the guide sleeve and keep the same from entering the joint between the die pot wall 60 and the guide sleeve.

Preparatory to forging a billet or blank between the die and mandrel, the same is heated to a high temperature, usually about two thousand degrees Fahrenheit, and it is therefore desirable to provide means for

cooling the die pot so as to prevent the same from being affected injuriously. The means suitable for this purpose which are shown in the drawings, particularly in Fig. 7, comprise a plurality of annular grooves 19 70 formed in the bore of the die pot body, a plurality of longitudinal connecting grooves 20 which are arranged in staggered relation to each other on opposite sides of the bore of the die pot body and each of which connects the corresponding parts of two adjacent annular grooves, an angular inlet passage 21 leading from the lowermost annular groove to the lower end of the die pot body adjacent to its outer corner, an annular supply passage 22 arranged at the upper end of the base outside of the shoulder thereof and communicating with the angular passage 21 and provided with a lateral inlet branch passage 23 which is adapted 80 to be connected with a supply of cooling medium such as water, and an outlet branch passage 24 extending laterally from the uppermost annular groove and adapted to be connected with a waste pipe or line in any 90 suitable manner. The water for cooling the die pot entering the supply branch 23 passes thence successively through the annular passage 22, the angular passage 21, the several annular and longitudinal grooves 19, 20, 95 and then escapes through the outlet passage 24, thereby reducing the temperature of the die pot and maintaining the same in a condition best suited for working the metal of the billet and prolonging the life of the 100 apparatus. Inasmuch as the angular supply passage 21 opens into the lower end of the die pot body and the space within the latter connects with the inlet 23 the wall of the die pot is free to rise and fall without disturbing the water connection with the source of supply.

Above the wall of the die pot the same is provided with a tubular cap 25 which has a central opening 26 for the passage of the 110 forming mandrel. This cap bears with the outer part of its lower or inner end against the upper end of the die pot body while its inner portion is provided with a downwardly-facing shoulder 27 which engages 115 the upper end of the die pot lining, but the bore of this cap is larger than the bore of the lining, as clearly shown in Fig. 1. This cap and the outer section or body of the die pot wall are detachably connected with each 120 other in order to permit the renewal of the lining when necessary, this connection as shown in the drawings, consisting preferably of a plurality of upright coupling bolts or rods 28 each of which passes through 125 a corresponding pair of coupling lugs 29, 30, on the outer side of the cap and the die pot body and provided with an upper screw nut 31 engaging with the upper side of the coupling lug of the cap and a lower screw 130

nut 32 engaging with the underside of the coupling lug of the die pot body.

The upward movement of the die pot and associated parts during the operation of forging a shell or similar tubular or cup-shaped article is preferably so timed that this movement ceases before the lower end of the die pot wall reaches the upper surface of the die pot bottom during which time the upward movement of the die pot is unrestrained. After the forging operation has been completed the finished forging is moved upwardly out of the die pot but in order to limit the upward movement of the die pot at this time and permit the finished forging to be removed therefrom, a stop device is provided which preferably comprises a plurality of bifurcated or notched stop lugs 33 arranged on the outer side of the guide sleeve and each receiving the lower end of one of the coupling bolts 28, the lower end of this bolt being provided with a crosshead 34 forming an upwardly-facing shoulder which is adapted to engage with the underside of the respective stop lugs 33. As the die pot rises during the operation of the forging blank the heads 34 of the several coupling bolts move idly upwardly toward the underside of the stop lugs and at the end of the movement of the die pot the same stop short of engaging the stop lugs 33, so that they do not exert any upward pressure against these lugs, otherwise there would be danger of either breaking these bolts or lugs owing to the enormous pressure under which the die pot is moved upwardly during the forging operation. When, however, thereafter the finished forging is ejected forwardly from the die pot by a comparatively low upward pressure against this forging, the heads of the several coupling bolts by engaging with the undersides of the stop lugs serve to arrest the further forward movement of the die pot and cause the forging to be ejected from the die pot.

The mandrel which forms the cavity within the hollow forging is preferably provided with a downwardly-tapering lower end or nose 35 and an upper cylindrical body 36 and the same is mounted at its upper end on the upper vertically movable platen of the press so that this mandrel is arranged axially in line with the die pot. In order to insure perfect concentricity of the mandrel relatively to the die pot when these parts coöperate for producing a cup-shaped forging from a solid blank, a centering or guiding device is provided which preferably is constructed in the form of a ring 37 the lower part 38 of its peripheral surface being preferably made of downwardly-tapering form and adapted to engage with a correspondingly inwardly-tapering face 39 in the upper part of the bore of the die pot cap. As the mandrel

moves downwardly its tapering nose first enters the centering ring or guide followed by its cylindrical body portion, whereby the mandrel is accurately centered with reference to the die pot before engaging the blank or billet in the die pot which is to be forged into cup-shape. After the forging operation has been completed, the mandrel is withdrawn so that the same is arranged above the die pot and associated parts a sufficient distance to permit the removal of the centering ring from the die cap and the forging from the die pot. In order to permit of readily applying the centering ring to the die cap and the removal therefrom as well as preventing this ring from being carried upwardly to an undue extent by frictional contact with the mandrel, the upper end of the die pot cap is provided on diametrically opposite sides with two stop hooks 40, 40 having their upper ends overhanging inwardly and providing the centering ring on its diametrically opposite sides with two stop lugs 41, 41 which play vertically in the spaces between the upper end of the die pot cap and the overhanging portions of the stop hooks. These spaces are sufficiently high so as to permit the centering ring to be moved laterally over the die pot cap and then dropped with its conical or tapering portion into engagement with the corresponding face of the die cap as well as the removal of the same in like manner. When, however, the mandrel is raised after a forging operation and the forging has a tendency to stick thereto, this centering ring is raised by such forging until the stop lugs of the centering ring engage with the overhanging upper ends of the stop hooks, thereby arresting the further upward movement of the centering ring and causing the finished forging to be stripped from the mandrel during the continued upward movement of the latter. This centering ring therefore operates both as a centering guide for the mandrel and also as a stripper for removing the finished forging therefrom.

For the purpose of quickly and effectively removing the finished forging from the die pot, an ejecting device is provided which may be variously constructed, but which as shown in Fig. 1 is constructed as follows:

42 represents a main or outer power cylinder arranged vertically in the base and adapted to be supplied at its lower end with a pressure medium such as water pressure by means of a supply passage 43 communicating with the lower end of the cylinder and adapted to be connected with a water supply under pressure. Sliding vertically within this cylinder is a main or outer piston 44 which is adapted to be raised by the admission of the pressure medium into the pressure cylinder. Extending upwardly

from this piston and through corresponding openings 45, 46 in the lower and upper sections of the die bottom is the outer or main section 47 of an ejector rod. The main ejector rod section is made hollow to form an inner or auxiliary power cylinder which communicates with the main cylinder by a passage 48 in the main piston. Within the auxiliary power cylinder is arranged an inner or auxiliary piston 49 which has connected therewith an inner ejector rod section 50 extending through the upper end of the outer ejector rod section.

The downward movement of the main piston 15 ton is limited by the bottom of the main cylinder and its upward movement by the top of this cylinder, and the downward movement of the auxiliary piston is limited by the lower end of the hollow ejector rod section 20 and its upward movement is limited by an internal downwardly-facing shoulder 51 formed at the upper end of the hollow piston rod section.

In the operation of this apparatus the blank 1 to be forged is introduced into the die pot while the wall thereof is in its lowered position and the mandrel elevated and the centering guide stripping ring removed from the die cap. This blank is nearly of the same diameter as the bore of the die pot lining so as to fit loosely therein and the same extends from the bottom thereof and preferably up to a line located below the upper end of the lining, for instance the line 35 52 shown in Fig. 1. The centering guide and stripper ring is now applied to the upper end of the die cap and then the plunger or mandrel is lowered so that it passes downwardly through the guide and stripper ring 40 and exerts endwise pressure against the blank from the upper toward the lower end thereof until the parts assume the position indicated in Fig. 2. During the initial portion of the downward movement of the mandrel in engagement with the blank, the latter is first spread until it completely fills the lower part of the die pot and firmly engages its bottom and lining. As the mandrel continues its downward movement in the blank 45 and forms a pocket or cavity 53 therein, the metal of the blank displaced by such movement of the mandrel is caused to move upwardly or lengthwise in the form of a tubular wall 54 through the space between the mandrel and the bore of the lining in a direction opposite to the movement of the mandrel. Owing to the tapering form of the nose or lower end of the mandrel, the metal blank is moved laterally by the wedge 50 action of the nose against the bore of the lining and produces a very powerful frictional contact between the blank and the lining, so that as the displaced metal moves upwardly between the mandrel and the die 60 pot wall, the latter is carried upwardly with

the metal of the blank until the forging operation has been completed by the time the lower end of the die pot wall has nearly reached the top on the die pot bottom. After the metal has been displaced laterally by the lower tapering portion of the mandrel and has moved upwardly beyond this tapering port of the same, it continues its upward movement between the cylindrical part of the mandrel and the adjacent cylindrical bore of the die pot lining under reduced frictional contact between the tubular wall 54 of the blank and the cylindrical part of the mandrel and the upper part of the die pot lining, so that the frictional resistance to the upward movement of the metal of the blank at this time is comparatively free.

After the forging operation has thus completed, the upper platen of the press is raised together with the mandrel, so that the latter is clear of the guide and stripper ring, and if during this movement the finished blank has a tendency to adhere to the mandrel, the latter will be stripped from the mandrel and caused to remain within the die pot by engagement of the upper end of the finished forging with the underside of the guide and stripper ring, which latter at this time is held against continued upward movement by engagement of its stop lugs with the stop hooks of the die cap. Thereafter the operator removes the centering and stripper ring and then admits water pressure into the lower end of the main power cylinder, so that the ejector rod sections by engaging with the lower end of the finished forging lift the same sufficiently high to permit the same to be reached by a pair of tongs and removed from the apparatus.

When admitting water pressure to the lower end of the outer power or main cylinder after a forging operation has been completed, the outer piston is first raised and its hollow rod section is lifted together with the forging engaged therewith until the outer piston engages with the top of the main cylinder. Thereafter the continually entering pressure medium into the outer cylinder passes through the passage in the outer piston and into the lower end of the hollow outer ejector rod, after which the inner piston is raised and its inner ejector rod section by engaging with the finished forging continues the upward lift of the latter until the inner piston engages with the upper shoulder of the outer ejector rod section at which time the finished forging has been lifted out of the die pot to such an extent that the same can be conveniently removed from the apparatus.

In the lowered or inoperative position of the ejector rod sections, their upper ends are arranged slightly below the upper or inner surface of the upper bottom section

forming a pocket therein, so that when the blank is forged into shape a boss 55 is formed centrally on the head 56 which closes the lower end thereof which boss is 5 subsequently used for centering the forging in a lathe during the operations of finishing the same into a shell or projectile.

Instead of constructing the ejector rod in the form of telescopic sections, as shown in 10 Fig. 1, the same may be constructed of a single section 57 which is connected with a single piston 58 in the power cylinder 42, as shown in Fig. 6.

By thus mounting the wall of the die pot 15 so that the same moves with the flow of the metal which is being forged, the power required to operate the press is materially reduced and the wear upon the bore of the die pot is minimized, so that the cost of maintaining the apparatus in perfect working 20 condition is materially reduced.

Furthermore, by employing the centering ring which maintains the mandrel concentric with the die pot, it insures the formation 25 of a cup-shaped or shell forging in which the wall is of uniform thickness in all parts of its circumference, and it also permits of producing such forgings regardless of whether the ends of the blank when 30 placed in the die pot are uneven by reason of irregularities in the fracture, cuts or breaks in the same when these blanks or billets are formed in sections from a long stock bar of this material.

35 As the nose of the mandrel enters the metal of the blank that portion of the metal between this nose and the bottom of the die pot is worked on the surface of the billet or blank, so that the metal in the forging is of more uniform consistency and any pores which may be present in the blank 40 are removed therefrom.

Moreover, by allowing the wall of the die pot to rise, the steel or metal is caused to 45 flow generally in the same direction in which this occurs when forming forgings of this character by forcing the same through a drawing ring, as has been heretofore practised, so that the present method 50 and apparatus retains all of the advantages inherent in the methods heretofore known with the added advantages derived from the improvements forming the subject of this invention.

55 This apparatus for practising our invention can be produced at considerably less cost than that required heretofore for this purpose, the forgings can be produced quicker and at less cost; the original cost 60 of equipment is reduced; a smaller press will suffice to operate the movable parts and owing to the reduced pressure which is required, the wear upon the mandrel is reduced and less frequent renewal of the same 65 is necessary.

We claim as our invention:

1. An apparatus for making shell forgings comprising a die pot having a tubular wall and a bottom arranged at one end of said wall, said wall being movable lengthwise relatively to said bottom, a mandrel adapted to enter the opposite end of said tubular wall, a base having a central body which carries said bottom and is engaged by the adjacent end of said wall and tubular guide arranged on said body and engaging slidably with the outer side of said wall, a packing interposed between said guide and wall, and a deflecting flange arranged on the outer side of said wall and overhanging the end of said guide. 70

2. An apparatus for making shell forgings comprising a die pot having a longitudinally movable tubular wall, a bottom projecting into one end of said wall and having a flange at its outer end, a mandrel movable lengthwise into said wall through the opposite end thereof, and a base having a central body which is provided at its top with a recess in which the flange end of said bottom is secured, a shoulder around said recess which is engaged by the inner end of said wall, and a tubular guide arranged outside of said shoulder and engaging slidably with the outer side of said wall. 75

3. An apparatus for making shell forgings comprising a die pot having a longitudinally movable tubular wall composed of a tubular body and a tubular lining engaging the bore of said wall, a bottom engaging with the inner end of said lining and a tubular cap engaging with the outer ends of said wall and lining, a longitudinally movable mandrel adapted to pass through said cap and enter the adjacent end of said lining, and means for limiting the movement of said pot wall away from the bottom thereof comprising coupling lugs arranged on said pot body and cap, a base carrying said bottom and provided with stop lugs, and bolts each connected with a corresponding pair of coupling lugs on said pot body and cap and provided with a head adapted to engage its upper side with the underside of one of said stop lugs on the base. 90

4. An apparatus for making shell forgings comprising a die pot having a tubular wall, a bottom arranged within the inner end of the wall and a tubular cap arranged on the outer end of the wall and having an inwardly tapering seat at the outer end of its bore and two inwardly overhanging stop hooks arranged on diametrically opposite sides of the outer end of the cap, a longitudinally movable mandrel adapted to enter said die pot from the outer end thereof, and a guide and stripper ring adapted to engage its bore with the periphery of said mandrel and provided with an inwardly tapering peripheral face which is adapt- 100

105

110

115

120

125

130

ed to engage the tapering seat of said cap and laterally projecting stop lugs which are adapted to engage with the overhanging parts of said stop hooks.

5. An apparatus for making shell forgings comprising a die pot having a longitudinally movable tubular wall and a fixed bottom arranged within the inner end of said wall, a longitudinally movable mandrel 10 adapted to enter said wall from the opposite end thereof, and means for ejecting the finished forging from said die pot comprising a telescopic ejector rod having a tubular outer section and an inner section arranged 15 within said outer section, an outer piston connected with said outer rod section, an outer power cylinder which receives said outer piston, and an inner piston connected with said inner rod section and movable 20 lengthwise in said outer tubular rod section.

6. An apparatus for making shell forgings comprising a die pot having a longi-

tudinally movable tubular wall and a fixed bottom arranged within the inner end of 25 said wall, a longitudinally movable mandrel adapted to enter said wall from the opposite end thereof, and means for ejecting the finished forging from said die pot comprising 30 a telescopic ejector rod having a tubular outer section and an inner section arranged within said outer section, an outer piston connected with said outer rod section, an outer power cylinder which receives said 35 outer piston, an inner piston connected with said inner rod section and movable lengthwise in said outer tubular rod section, means for supplying pressure medium to said power cylinder and tubular rod, and means for limiting the longitudinal movement of said rod sections and piston relatively to each other and to said die pot 40 bottom.
